UNITED STATES PATENT OFFICE.

ELMER T. AYERS, OF SPARTA, TENNESSEE.

PROTRACTOR AND GAGE.

1,319,942.

Specification of Letters Patent. Patented Oct. 28, 1919.

Application filed June 2, 1919. Serial No. 301,204.

To all whom it may concern:

Be it known that I, ELMER T. AYERS, a citizen of the United States, and a resident of Sparta, in the county of White and State 5 of Tennessee, have invented certain new and useful Improvements in Protractors and Gages, of which the following is a specification.

My present invention relates generally to 10 protractors, and more particularly to a combined protractor and gage, my object being the provision of a simple, inexpensive implement of this nature susceptible of ready adjustment and manipulation, and capable of 15 a variety of uses and of efficient and effective results.

Further objects, relating more particularly to the details of construction of the device, will plainly appear in the course of 20 the following description, reference being made to the accompanying drawing, which forms a part of this specification, and in which:—

Figure 1 is a perspective view illustrating 25 my invention complete,

Fig. 2 is an elevation of a portion thereof looking from the opposite side as compared to Fig. 1, and

Fig. 3 is a sectional view taken on line 30 3—3 of Fig. 2.

Referring now to these figures, my invention proposes the use, in a device of this nature, of a square generally indicated at 10, which may be calibrated along its legs 35 11 and 12 in the usual way, and one leg of which, commonly known as the blade, is provided with a lengthwise slot 13 for the major portion of its length.

The square thus formed is utilized in connection with a clamp, consisting of spaced 40 facing clamping members 14 and 15, approximately semi-circular in form, of which the member 15 is slightly reduced with respect to the member 14 so that the scale or 45 calibration 16 of one face of the member 14 facing the member 15, will be exposed along the peripheral edge of the latter, both of these members 14 and 15 having straight edges 17, which, from an inspection of Figs.

50 2 and 3, come into registry, it will be noted, when one of the index marks 18 of the member 16 as seen in Fig. 1, is opposite the zero point of the scale 16 of the member 14.

These members 14 and 15, between which 55 the slotted blade 11 of the square is extended, are connected by a central pivot and

clamping bolt 19, as seen in Fig. 3, having a wing nut 20 coöperating therewith and readily manipulated thereon for the purpose of securing the blade 11 of the square 60 in lengthwise adjusted relation, as well as maintaining the square in the desired angular relation with respect to the member 14, for which latter purpose the blade 11 of the square is extended through a slot 65 along the inner face of the member 15 as seen in Fig. 1 so that the square is angularly adjustable with the member 15 in respect to the member 14.

Along its straight edge 17, the member 70 14 has a laterally projecting rib 21 which extends beyond the outer face of the said member, as well as projecting at its ends beyond the sides of the member, and the upper face of this laterally projecting rib 75 21, which is parallel to the straight edge 17, has a spirit level 22 which thus coöperates with the straight edge 17 and is capable of coöperation with the tongue of the square.

The clamping bolt 19, as shown, projects 80 through the slot 13 of the blade 11 of the square so that the clamp as a whole is thus adjustable along the blade 11 for the full length of its slot 13 and the member 15 of the clamp, together with the square, may be 85 adjusted angularly with respect to the member 14, at any point along the length of the adjustment of the clamp upon the square, it being borne in mind of course, that the slot of the member 15 holds the square so 90 that its blade 11 is at exactly right angles with respect to the straight edges 17, when the straight edges of the two members 14 and 15 of the clamp are in alined relation.

It is furthermore obvious that the outer 95 surface of the member 15 may, if desired, be provided with various scales and rules utilized in plotting various portions of a building, for instance, with the protractor, and it is obvious that for purposes of convenience, a vernier may be utilized as at 23, upon the outer face of the member, coöperating with the degree marks of the protractor scale 16 of the member 14.

It is also obvious that my invention is 105 capable of a variety of uses, as well as of ready, quick adjustment and the production of effective, efficient results, and it is furthermore obvious that I obtain these advantages by a construction which is at once 110 simple, strong and durable and capable of utilizing in connection with the clamps

thereof, a square of conventional form, by simply forming a slot 13 in one of the legs of the square.

I claim:—

- 5 1. An implement of the character described, comprising a square, the blade of which is provided with a longitudinal slot, a pair of clamping members between which the slotted blade of the square is extended and adjustable, one of said members being provided in its inner face with a groove in which the said slotted blade of the square is slidably disposed, said clamping members having straight edges arranged to aline with 10 one another and arranged at right angles with respect to the groove of the first mentioned clamping member, the second clamping member having a rib outstanding laterally therefrom along its said straight edge, 15 a spirit level carried by the said rib, and a clamping and pivot bolt extending through and connecting the said clamping members and projecting also through the slot of the said square.
- 20 2. An implement of the character described, comprising a square having the blade thereof provided with a longitudinal slot, a clamp including side members, one of which has a groove in its inner face in which the 25 slotted leg of the square is slidable, a clamping and pivot bolt connecting the said members and extending through the slot of the square, said members being generally of semi-circular form and having straight 30 edges arranged to register with one another and disposed at right angles with respect to the square-receiving groove, as described.
- 35 3. An implement of the character described, comprising a square having the

blade thereof provided with a longitudinal slot, a clamp including opposed clamping members, between which the slotted blade of the square is extended, a clamping and pivot bolt connecting the said clamping members and extending through the slot of the said blade of the square, one of said members being slightly reduced with respect to the other and having an index point, the other of said members having on its inner face a protractor scale with which the index point 40 of the first member co-operates, said first named member having a groove in which the slotted blade of the square is disposed, and the other of said members having a straight edge and a rib outstanding therefrom along the straight edge, and a spirit level carried by the said rib, for the purpose 45 described.

4. An implement of the character described, comprising a square having one 50 longitudinally slotted leg, a clamp including opposed clamping members, one of which is provided with a protractor scale and the other of which has an index point 55 co-operating with the scale, said last named member having a groove in its inner face in which the slotted leg of the square is slid- 60 able, a clamping and pivot bolt extending through and connecting the said members, said members having straight edges ar- 65 ranged to register and of which the straight edge of the last named member is disposed at right angles with respect to the groove there- 70 of, the said first named member having a laterally outstanding rib along its straight 75 edge, and a spirit level in the said rib, as de- scribed.

ELMER T. AYERS.
